RECORDING SYSTEM AND APPARATUS.

1,309,413.

Specification of Letters Patent.

Patented July 8, 1919.

Application filed December 28, 1917. Serial No. 209,258.

To all whom it may concern:

Be it known that I, RICHARD M. HOPKINS, a citizen of the United States of America, and a resident of Rutherford, in the county of Bergen and State of New Jersey, have invented a certain new and useful Recording System and Apparatus, of which the following is a specification.

My invention relates to systems for recording the signals of watchmen's signal boxes and the like, and constitutes a modification of, and improvement on, the system for the same purpose set forth in my application for Letters Patent, Serial No. 144,952, filed January 27, 1917. In that application I have described a system and apparatus wherein a suitable record sheet or surface, mounted upon a movable carrier, is arranged to have marks or impressions formed upon it by means of so-called punches. This recording sheet or surface is divided up into separate zones or areas corresponding to different groups of signal boxes or transmitters, and there is a single punch or marker for each such zone or area, together with means, under the control of the signals of the several signal boxes, for selecting a particular punch or marker and for moving that punch or marker to a particular position with respect to the said recording sheet or surface; the result being that such selected punch or marker is caused to make on or in the said recording sheet or surface a mark distinctive, by reason of its position, of the particular signal box or transmitter which was operated.

According to my present invention, instead of employing punches or markers, one for each such zone or area of the record sheet or surface, I employ spark points together with means for making, by an electric spark, a perforation or other mark in or on the record sheet or surface, and I employ a master selector and a plurality of secondary selectors controlled thereby, for selecting the particular spark point which corresponds to the particular signal box or other transmitter operated. Thereby I dispense with a certain amount of complication attendant upon the use of mechanical punches or markers together with means for shifting same as a part of the selecting operation. Other features of my invention will be pointed out hereafter.

The object of my invention is to simplify recording systems and apparatus involving the use of selecting means for determining a particular point on the record sheet or surface on which a mark is to be made.

I will now proceed to describe my invention with reference to the accompanying drawings, showing, more or less diagrammatically, apparatus in circuits constituting one embodiment of my invention, and will then point out the novel features in claims.

In the said drawings:

Figure 1 is a diagram illustrating a signal box circuit with a plurality of groups of signal boxes therein, and also illustrating diagrammatically the several selectors, relays, and record making devices of the system.

Fig. 1^a shows an elevation of a characteristic break wheel and its co-acting brush or pen, such as may be used in signal boxes, such as are illustrated diagrammatically in Fig. 1.

Fig. 2 shows, diagrammatically, a rotary drum or record-sheet carrier, such as may be used for carrying the record-sheet of a recorder, and shows in connection therewith spark points and contact wheels whereby sparks may be projected through the paper or record-sheet for the purpose of making records on such sheet.

Fig. 2^a shows, more or less diagrammatically, mechanism for moving this drum or record-sheet carrier.

Fig. 3 shows a side elevation of the master selector and the primary selector, combined to form one mechanism; Fig. 4 is a central longitudinal section of the mechanism shown in Fig. 3 with the central portion of the mechanism broken away.

Fig. 5 is a detail perspective fragmentary elevation of the release magnet, pole piece, and armature of the primary selector; Fig. 6 is a top view of the selector mechanism shown in Fig. 3.

Referring first to Fig. 1; A designates a signal box circuit comprising a plurality of groups of signal boxes B, the number of boxes in each group being variable. Each such box may be understood to comprise a signal-transmitting mechanism of the familiar toothed wheel and pen type, as shown, for example, in Fig. 1^a; which mechanism, when operated, will break and complete the

circuit A according to some prearranged signal, distinctive of the particular box to which the transmitting mechanism operated belongs. Such signal may be considered to be a box number, each number to consist of two digits; one digit, preferably the initial digit, of the signals of the boxes of any one subscriber, *i. e.*, the initial digit of all of the boxes of any one group, will be the same. 5 In other words, the signals of all of the boxes of one group will begin with the digit "2;" the signals of all of the boxes of another group will begin with the digit "3;" and so on. It should be explained, further, 10 that the term "digit" is employed herein in a special sense. In the ordinary sense the term "digit" includes any of the numerals from one to nine inclusive. The break wheels of the signal boxes comprise teeth, 15 with intervening notches, arranged in two groups separated by spaces; and the number of teeth in any one of these groups may exceed 9; yet it is convenient to speak of the numeral represented by the teeth of any one 20 such group as a digit, and no departure from principle is involved in so doing.

C designates a battery or other source of current supply, in circuit A, and D designates a main line relay, in said circuit A, 30 which repeats the signals of boxes B in the local or central station circuits, as herein-after described. The elements of the digits of the box signal are repeated by said relay D into the actuating magnet *a* of a primary 35 selector G as follows:

From supply conductor X through conductor 1 to the ratchet magnet *a* of selector G, (hereinafter described), conductor 2, the first contact point and contact arm *b* of a 40 master selector F, (hereinafter described), and conductor 3 to the armature and rear contact stop of main line relay D, and thence through conductor 4, and common return conductor 7, to the other supply conductor 45 Y. As the armature of main line relay D falls and rises during the operation of any one of the call boxes, this circuit 1-2-3-4-7 will be closed and broken successively, and it will be obvious that the impulses of 50 the first digit of such signal box so operated, as such impulses are transmitted through magnet *a* of selector G, will cause the contact arm *b* of that selector to travel successively over the contact points of the selector 55 until, at the end of the first digit of the box number, that contact arm *b* will have come to rest on a particular contact point of the selector G, thereby forming a circuit through one of the wires 21-26 leading from the 60 contact points of said selector G to one of the selecting magnets L-Q (the function of which magnets will be explained herein-after).

E designates a slow acting "governor" relay, the magnet of which is connected by

conductor 8 to supply conductor X and is connected by conductor 9 to the armature of line relay D. It will be obvious that each time the armature of relay D is retracted, circuit is completed through the magnet or 70 relay E, and through conductor 7. However, this relay E is so slow in action that while its armature *e* is moved away from the corresponding rear contact stop during the first closure of the contact of relay D in the 75 transmission of a digit, it does not again contact with its rear stop during the spaces between closures by relay D during the transmission of that digit. The longer spaces, between the digits of the box signals, 80 do, however, cause the armature of relay E to close contact with its rear contact stop, thereby closing a circuit from conductor X through conductor 10, the ratchet magnet *a* of master selector F and conductor 11, the 85 rear contact stop of relay E, armature *e* and thence through conductor 7 to supply conductor Y. Closing this circuit 10-11 causes the contact arm *b* of selector F to move to the second contact point of that 90 selector, thereby cutting out of circuit the ratchet magnet *a* of selector G and cutting into circuit 1-12-3-4-7, the ratchet magnet *a* of a third selector, H.

The armature of relay E is attracted during the transmission of the impulses of the second digit of the box number; but during the space following the second digit, the armature of relay E is again released, thereby operating magnet *a* of master selector F 95 and moving the contact arm *b* of that selector to the third contact point of the selector. The instant ratchet magnet *a* of master selector F has been so energized, and has moved arm *b* of master selector F into 100 contact with the third contact point of that selector, a circuit is completed from supply conductor X through conductor 8, magnet E, conductors 9 and 3, contact arm *b* of selector F, the third contact of that selector, 105 dividing point *x*, the release magnet *m*, of selector H, the contact arm *b* of selector G, the contact point of that selector on which such arm *b* is then resting, the selected magnet of series L-Q and the return conductor 110 to which those magnets are connected, to supply conductor Y. The armature *e* of relay E being thereby attracted, the circuit of magnet *a* of the master selector F is broken; and as the release magnets *m* of 115 selectors F and G have been energized simultaneously by closure of a circuit from supply conductor X, conductor 8, magnet E, conductors 9 and 3, contact arm *b* of selector F, the third contact of that selector, point *x*, 120 conductor 18, and conductor 18' to the other supply conductor Y, the arms *b* of selectors F, G, and H are also returned. As herein-after described, the release of arm *b* of selector G occurs upon the breaking of the 125 130

circuit of its magnet m by the return to normal of arm b of selector F, following energization of magnets m of selectors F, G, and H. The arms b of selectors F, G, and H when permitted to return, move to a point somewhat beyond or in rear of the first contact points of those selectors. The magnet a of selector F being in a circuit which is normally closed, and that magnet 5 10 a being energized immediately upon the return of the arm b to normal, immediately moves such arm b to the first contact point of selector F and holds it there until, the circuit of magnet a being broken and subsequently completed, the ratchet pawl, hereinafter referred to, operated by such magnet a , retreats, engages another tooth of the ratchet operating-mechanism of that arm b , and moves such arm b to the second point 15 20 of the selector.

Magnets a of selectors G and H are each in a normal open circuit, and, therefore, the arm b corresponding to each such magnet a , when returned, remains in rear of the 25 first of this series of contacts of the selector until, through the receipt of a corresponding digit of the signal of a box, that arm b is advanced to the first of such series of contacts, and possibly to some other contact 30 point of the selector.

n designates a so-called "spark relay" connected in multiple with the release magnets m of selectors F, G, and H. When the magnet of this relay n is energized, it closes the 35 primary circuit of a spark coil o . Each of the relays $L-Q$, when its magnet is energized, closes a circuit path from the secondary of the spark coil o to a contact wheel p opposite a corresponding "sectional contact" $L'-Q'$ on the drum 51 of the recorder; such drum, as indicated in Fig. 2, being divided into sections each having a conductive surface, L' or N' , etc., insulated from all of the other such conductive surfaces but arranged to be connected by its wheel p and by the contacts of its corresponding relay $L-Q$ to the secondary of the spark coil o . It will be apparent that selector G, by its operation, selects a particular one of such sectional contacts. Opposite each of these sectional contacts $L'-Q'$ is a row of spark points $L''-Q''$, and one of these spark points of each such set is connected to a corresponding contact 50 55 of selector H. It will be apparent that the effect of the operation of selector H is to select a particular spark point of a set opposite the particular sectional contact already selected by selector G. Since the 60 65 spark relay n is energized at the instant of energization of release magnet m of selector H, at the instant of closure of the contacts of spark relay n a spark is propagated across the gap between the particular sectional contact of series $L'-Q'$ already se-

lected, to the particular spark point of series $L''-Q''$ already selected, and thereby a mark is made on the paper sheet carried by the recorder drum, in accordance with signal transmitted by the particular call 70 box operated. From the sectional contacts of series $L'-Q'$ the spark current passes back through rollers p to return.

While the record sheet intervenes between the roller p and the conductive surfaces 75 $L'-Q'$, yet the current of the spark, being of high tension, will pass through the paper from the conductive surface $L'-Q'$ to such roller p ; and in practice it is found that no mark is made by the current in so passing, 80 this being due probably to the fact that the rollers p are in actual contact with the record sheet.

The drum 51 is rotated by means of an electrically operated step by step mechanism 85 55, (Fig. 2^a) itself operated by a time movement R and relay S (Fig. 1).

Selectors.—The selectors F, G, and H of the recorder are similar in construction; G and H being identical, except as to the number of contact points, while specific differences between selector F and selectors G and H will be pointed out hereinafter. I will describe only selector G, since selector H is exactly similar except in the difference in contact points.

Each of these selectors comprises a row of contact points, a contact arm b adapted to travel over these points successively and to make contact therewith, a ratchet wheel 81 100 connected to such arm b to move the same, a ratchet magnet a , an armature 82 therefor, a spring-returned ratchet-pawl 83 operated by said armature 82, and engaging the teeth of ratchet wheel 81 to rotate said wheel, a holding pawl 84, and a release magnet m which, in the case of selector F, when energized, pulls pawl 84 clear of the ratchet wheel 81, so permitting return movement of that ratchet wheel and contact arm b under the 110 influence of a spring 85. The manner of release of arm b of selector G will be explained hereinafter. When ratchet magnet a of selector G is energized, the first portion of the resulting movement of the ratchet 115 pawl 83 of that selector moves that pawl into engagement with a tooth of the corresponding ratchet wheel 81; further movement of that pawl advancing the ratchet-wheel through the space of one tooth, whereupon the ratchet wheel is held, temporarily, against return, by holding pawl 84. Successive energizations of the ratchet magnet a of either selector advance the ratchet wheel 81 a number of spaces corresponding to the numerical value of the digit of the box signal by which that ratchet magnet is being operated.

The pawl 84 of selector G (the right hand selector shown in Figs. 3 and 4) carries a 130

pawl 84^a which, when the ratchet wheel 81 is in normal position, is held in the position shown by a pin 81^a carried by ratchet wheel 81. When wheel 81 of selector G is advanced by ratchet pawl 82, a spring 84^b forces a pawl 84^a into position for engagement with an extension of armature 84^c. When magnet m of selector G is energized, the armature 84^c is pulled up so that the extension of said armature engages with the hook of pawl 84^a. Upon deenergization of such magnet m and consequent retraction of armature 84^c, the extension of such armature, being still in engagement with pawl 84^a, will raise that pawl, and with it, the holding pawl 84, so permitting return of ratchet wheel 81; and at the end of such return pin 81^a disengages 84^a from 84^c.

Fire signals.—Fire signals are usually distinguished from watchmen's signals by a dash, or by a Morse character containing a dash, preceding or following the box number; also, by giving the box number of signal a greater number of times than for the 20 watchmen's signal. Signal boxes which distinguish in this manner between fire signals and watchman's signals are well known and in common use. Such boxes commonly comprise means whereby the distinguishing signal (the dash of the Morse letter containing the dash) is omitted when sending watchmen's signals. The break wheel 90 shown in Fig. 1^a, which wheel is characteristic of break wheels forming a part of the transmitting mechanism of combined watchmen and fire alarm boxes, has teeth for transmitting not only the box number (42, in the particular instance shown) but also the Morse letter F (dot, dash, dot). It is to be understood 30 that, for watchmen's signals, the boxes B are provided with one of the well-known means for eliminating this letter F from the watchman's signal; but that when a fire signal is sent from any of these boxes the said Morse letter F is included as a part of the signal. This special fire signal is made evident at the central station as follows:

U and V, Fig. 1, are slow-acting relays, preferably similar to the relay E already 50 described. These two relays are connected in what may be termed "cascade series"; that is to say, the contacts of relay U control the magnet circuit of relay V. The circuit for the magnet of relay U is from supply conductor X through conductor 8 to magnet of relay U, thence through conductor 13 to the armature of relay D, thence through conductors 4 and 7 to return at Y. This circuit is closed each time the pen 91 55 (Fig. 1^a) of the box rides upon one of the teeth of the signal wheel 90, and when in consequence, contact is broken between 91 and 92, and the armature of relay D drops. The circuit for relay V is from X and 8 60 through the contacts of relay U and thence, 65

when these contacts are closed, through the magnet of relay V and to the armature of relay D and thence through the conductors 4 and 7 to return at Y. The retardation obtained by employing two such relays in cascade series, and by the proper adjustment of the relays, is such that the contacts of relay V are not closed while pen 91 is passing over the short teeth of the box number of break wheel 90, but are closed during the passage 70 of pen 91 over the dash of the Morse letter F. The contacts of relay V, so closed, complete a circuit through the magnet of a "drop relay" W, as follows: from supply conductor X, conductor 14, conductor 3, 80 conductor 15, magnet of relay W, contacts of relay V, conductor 16, magnet m of selector F, magnet m of selector G, and back to return at Y. This relay W has a drop armature, which, when attracted toward the magnet of the relay, brings together contacts 5 and 6, and thereby places a register 17 in circuit between the armature of relay D and supply conductor X. The register will then record subsequently received box number signals.

The drop armature of relay W is restored by hand (or otherwise) to open contacts 5 and 6 and throw the register 17 out of action. The mere deenergization of the magnet of the relay W does not restore the armature.

The sending of the Morse letter F (dot, dash, dot) does not affect the selectors F and H, because there being in this letter F 100 no space equivalent to a space between digits, governor relay E is not operated. Selector G may be operated, but will be restored automatically. The relay E is operated by the impulses of the letter F, breaking the circuit of magnet a of selector F; and since relays U and V close the circuits of release magnets m of selectors F and G during the dash of the letter F, by a circuit from conductor X through conductors 14 110 and 13, magnet of relay W, contacts of relay V, conductor 16, magnets m of selectors F and G, and thence to Y, arm b of selector F drops back of the first contact point of selector F, and arm b of selector G also drops 115 back; but when, during the long space following the letter F, the armature of relay E drops, the circuit of magnet a of selector F is completed again, and arm b of that selector is brought back to the first contact point 120 of that selector.

Imperfect or clash signals.—It does not always happen that signals received are perfect. Through various circumstances signals are sometimes incomplete or faulty, and 125 sometimes two or more boxes are operated simultaneously (that is to say one box is started before another box has finished) producing what are known as "clashes." These clashes, or false signals, usually occur 130

through one watchman sending in a signal out of time and while another watchman is already sending in a signal, or through a fire signal being sent from one of the boxes 5 while a watchman's signal, or a fire signal, is being sent from another of the boxes. Such clashes or false signals may be of various characters. A false signal may consist of a single impulse only, or it may consist of a plurality of impulses greater than the number of impulses in the first digit of a regular signal, and without any long space such as separates the digits of a regular signal; or a false signal may be divided into 10 digits, but the first digit may comprise a greater number of impulses than can be comprised in the first digit of a regular signal; or, the false signal, or clash signal, may contain a dash similar to that of the Morse 15 character "F", with or without a long space, such as the spaces between digits.

It is desirable, when possible, to record such false signals, or clashes; and to that end upon the drum 51 of the recorder has been 20 provided a separate section 93 for the purpose of recording clashes or other imperfect signals. Referring to Fig. 1, it will be noted that there are two relays, T^2 and T^3 , connected in cascade series in the conductor 10 25 on opposite sides of the resistance 94. By cascade series is meant that the magnet circuit of one relay, T^2 for example, passes through the armature contacts of the other relay, T^3 , so that the circuit of relay T^3 must 30 be closed before the circuit of relay T^2 can be closed (a series of relays connected in cascade series constitutes, in effect, a single relay of very slow acting character, and in the following claims such a series of relays connected 35 in cascade series is to be considered as included within the term "relay"). Another 40 resistance, 94^a, usually a tungsten lamp of about 25 watts, is also interposed in the circuit 10, and serves both as a resistance and as 45 an indication of the condition of the circuit in which it is interposed.

On the drum is provided a conductive section, 96, corresponding to a spark point, 97, and a roller p , whereby a record may be 50 made of clashes and imperfect signals, in the same manner that records are made on other portions of the record sheet, by sparks propagated from the sets of spark points $L''-Q''$.

It is important, not only that clash signals or other imperfect signals, including false signals, shall be recorded on the portion of the record sheet corresponding to the portion 55 93 of the drum, but also it is important that such a clash signal, or imperfect signal, shall not be recorded in any of the columns allotted for regular signals; likewise, it is important that no clash signal, or other false signal, shall leave the arm b of 60 the master selector F on the second or inter-

mediate contact point of that selector; for, if this arm were left on this second or intermediate contact point, the selecting mechanism would be "locked up".

In my companion application, Serial No. 70 171,940, filed May 31, 1917, and also in another companion application of even date herewith, filed Dec. 28, 1917, Sr. No. 209,257; I have illustrated and described 75 means for the recording of clash signals and other imperfect signals, for preventing such clash, or imperfect, signals from being recorded in the columns allotted for regular signals, and for preventing the locking up 80 of the selecting mechanism through the leaving of arm b of master selector F on the second or intermediate contact point of that selector. In the present application I illustrate, and will now describe, means for such 85 purposes, corresponding to the means for such purposes illustrated and described in my said application, filed Dec. 28, 1917, Sr. No. 209,257, but adapted for making records of clash signals and other imperfect signals by means of spark apparatus. 90

Obviously, in the case of a clash or false signal, consisting of a single dot, or of a plurality of dots greater than those contained in a regular digit signal, there will follow a 95 space until the restoring devices, such as herein described, function. The slow action relays T^2 and T^3 (together constituting, as already stated, a single slow acting relay) are provided to distinguish between the long spaces between digits of a regular signal, 100 and the longer spaces following a false signal; that is to say, these relays are provided to permit of time intervals, in excess of the length of the spaces between digits of regular signals, after which the said restoring 105 means shall come into action, together with the clash recording relay Z . The circuit connections by which the circuit of the magnet of relay Z is closed through the contact points of relays T^2 and T^3 are as follows: 110 from conductor X , through conductor 14, conductor 3, conductor 95, magnet of relay Z , conductor 98, contact points of relay T^2 , conductor 99, contacts 19 and 20 of master selector F (contact being closed between 19 115 and 20 when arm b of master selector F is on its second contact point) point x , release magnet m of selector F , release magnet m of selector G , and through conductor 18' to return conductor Y ; also from point x through 120 magnet m of selector H , the contact arm b of selector G and the particular contact point of that selector, on which arm b is then resting, and the spark relay to return conductor Y . By the closing of the circuits 125 mentioned all of the selectors of the recorder will be returned to zero.

The above described arrangement will cause the registration of a clash by the clash magnet Z , and also the return of the selectors 130

to normal, in case the signal containing the clash is of such a nature as to leave the contact arm *b* of selector F upon the second contact point of that selector.

- 5 A false signal, consisting of a single impulse only, will have the effect of moving the contact arm *b* of selector F to its second contact point; and will also have the effect of moving the arm *b* of selector G to the contact point connected to punch magnet L; but since selector H has not been operated by such a signal, no registration by spark points of series L' will occur, the clash being represented only by the record made by the 10 clash magnet. Similarly, other false signals consisting of a plurality of impulses not separated by a long space, such as a space between digits, will not cause the operation of the selector H, and so will be represented 15 on the record sheet only by the mark made by the spark point of clash magnet Z. In case the false signal contains a number of impulses greater than the impulses in the first digit of a regular signal (and with no 20 long space between impulses) or, in case the false signal consists of a plurality of digits, the first of which contains a number of impulses greater than the impulses in the first digit of a regular signal, then the arm *b* of selector G will come to rest on a final contact point of that selector which is connected through the circuit closed by relay T² and through the contacts of magnet Z to this 25 final contact point of the selector and thence through the arm *b* of that selector to the restoring circuits; and thereby the various 30 selectors will be restored to zero.

There are certain other kinds of clashes, namely, those which contain a dash similar 40 to that of the Morse character "F" and which do not contain spaces, other than those between the regular impulses of a digit, which will not be recorded in the clash column, by the means just above described. Such signals, however, viz., clash 45 signals containing a dash similar to that of the Morse character "F" and not containing long spaces, will operate the drop relay W through the action of the relays U and V, and so will cause the operation of the register 50 17 and the return of the recorders to normal, substantially in the same manner as described in my said prior application, Serial No. 171,940, *i. e.*, as follows:

55 Should, for any reason, a signal containing a dash similar to that of the Morse character "F" and not containing spaces other than those between digits be received, then, upon the reception of the dash, relays 60 U and V will be operated, relay V closing a circuit as follows: from conductor X, through conductor 14, armature of relay D, conductor 3, magnet of drop relay W, contacts of relay V to point *x*, and thence 65 through the clearing circuits containing the

release magnets, as described heretofore. The magnet of drop relay W being energized, the register 17 is placed in circuit, and the remainder of such a clash signal will be recorded on the register.

In my prior application, Serial No. 171,940, above referred to, I have disclosed recording apparatus wherein a master selector F, similar to the master selector F of the present application, is provided with 70 contact points similar to the contact points 75 19 and 20 of the present invention; and have also provided a slow acting relay in series with a ratchet magnet of the master selector. But the connections of the contact 80 points 19 and 20 and of the slow acting relays T² and T³ of the present case are quite different from the connections of the corresponding parts in my said prior application; and attention is drawn to this fact to avoid 85 possible confusion.

What I claim is:

1. In a recording system, the combination with signaling means adapted for producing signals comprising a plurality of 90 groups of impulses, of a plurality of recording means each comprising a plurality of spark points adapted to project electric sparks and thereby to make records on a recording surface, and selecting means 95 adapted to be actuated by the signals of said signaling means and adapted to select a particular recording means and a particular spark point of that recording means, under control of said signals.

2. In a recording system, the combination with a line relay and signaling means adapted for actuating said relay by signals comprising a plurality of groups of impulses, of a plurality of recording means 105 each comprising a plurality of spark points adapted to project electric sparks and thereby to make records on a recording surface, a plurality of selectors arranged to be connected successively to said line relay for 110 actuation thereby, and a master selector arranged to switch said first mentioned selectors into connection with said line relay successively, said selectors arranged to select a particular recording means and a 115 particular spark point of that recording means, under control of said signals.

3. In a recording system, the combination with a line relay and signaling means adapted for actuating said relay by signals 120 comprising a plurality of groups of impulses, of a plurality of recording means each comprising a plurality of spark points adapted to project electric sparks and thereby to make records on a recording surface, a plurality of selectors arranged to be connected successively to said line relay for 125 actuation thereby, a master selector arranged to switch said first mentioned selectors into connection with said line relay 130

successively, and a governor relay controlling said master selector and itself controlled by spaces between digits of the signals.

5 4. In a recording system, the combination with a record-sheet carrier divided into a plurality of sections each having a sectional contact, of a plurality of recording means located opposite said sectional contacts respectively and each comprising a plurality of spark points adapted to project electric sparks to said sectional contacts, and thereby to make records on said record sheet, signaling means adapted for 10 producing signals comprising a plurality of groups of impulses, and selecting means adapted to be actuated by the signals of said signaling means and adapted to select a particular recording means and a particular 15 spark point of that recording means, under control of said signals, said selectors comprising restoring means actuated upon completion of the selection operation, a spark relay in circuit with said restoring 20 means, and a spark coil controlled by said spark relay and arranged upon actuation of that relay to project a high tension current impulse through the selected spark point to the selected sectional contact.

5 5. In a recording system, the combination with a record-sheet carrier divided into a plurality of sections each having a sectional contact, of a plurality of recording means located opposite said sectional contacts respectively and each comprising a plurality of spark points adapted to project electric sparks to said sectional contacts, and thereby to make records on said record sheet, signaling means adapted for 25 producing signals comprising a plurality of groups of impulses, selecting means adapted to be actuated by the signals of said signaling means and adapted to select a particular recording means and a particular 30 spark point of that recording means, under control of said signals, a spark relay arranged to be operated by the final selector upon 35 completion of the selection operation, and a spark coil controlled by said spark relay and arranged upon actuation of that relay to project a high tension current impulse through the selected spark point to the selected sectional contact.

6 6. In a recording system, the combination with a record-sheet carrier divided into a plurality of sections each having a sectional contact, of a plurality of recording means located opposite said sectional contacts respectively and each comprising a plurality of spark points adapted to project electric sparks to said sectional con-

tacts, and thereby to make records on said record sheet, signaling means adapted for 55 producing signals comprising a plurality of groups of impulses, selecting means adapted to be actuated by the signals of said signaling means and adapted to select a particular recording means and a particular 60 spark point of that recording means, under control of said signals, said selectors comprising restoring means actuated upon completion of the selection operation, a spark relay in circuit with said restoring 65 means, and a spark coil controlled by said spark relay and arranged upon actuation of that relay to project a high tension current impulse through the selected spark point to the selected sectional contact.

7 7. In a recorder, the combination with a record-sheet carrier divided into a plurality of sections, and provided with a sectional contact for each such section, of a plurality of recording means each comprising a plurality of spark points adapted to project electric sparks and thereby to make records on a recording circuit carried by said carrier, and a plurality of return current devices likewise located opposite said 80 sectional contacts and adapted to provide a return path for the current from said sectional contacts through the record-sheet to said return contact devices.

8 8. In a recorder, the combination with a record-sheet carrier divided into a plurality of sections, and provided with a sectional contact for each such section, of a plurality of recording means each comprising a plurality of spark points adapted to 90 project electric sparks and thereby to make records on a recording circuit carried by said carrier, and a plurality of return current rollers likewise located opposite said sectional contacts and adapted to provide 95 a return path for the current from said sectional contacts through the record-sheet to said return contact rollers.

In testimony whereof I have signed this specification in the presence of two subscribing witnesses.

RICHARD M. HOPKINS.
